Orchard Lake, Mich., assignors to Soss Manufacturing
Company, Detroit, Mich., a corporation of Nevada

Filed Mar. 23, 1967, Ser. No. 6,352

Term of patent 14 years

(Cl. D26—1)

FIG. 1 is a front perspective view of a voltage tester, showing our new design, the testing probes being shown in their retracted positions.

FIG. 2 is a front view thereof.

FIG. 3 is a side view thereof.

FIG. 4 is a side view opposite to that shown in FIG. 3.

FIG. 5 is a top view thereof.

FIG. 6 is a bottom view thereof with the cord omitted.

FIG. 7 is a rear view thereof.

FIG. 8 is a front perspective view thereof with the testing probes in their extended positions.

FIG. 9 is a rear perspective view thereof with the probes in their extended positions.

The coiled cord is shown either fully or partially in broken lines in some of the drawing views for ease of illustration, and the essential features of the design reside in the full line portions.

We claim:

The ornamental design for a voltage tester, substantially as shown and described.
